CLAIM

I claim the ornamental design for a corrugated window well with a face having the appearance of granite, as shown.

DESCRIPTION

FIG. 1 is a perspective view from slightly above a front and right of the corrugated window well with a face having the appearance of granite.

FIG. 2 is an elevation view of a face of FIG. 1.

FIG. 3 is an elevation view of a back of FIG. 1.

FIG. 4 is an elevation view of a right side of FIG. 1.

FIG. 5 is an elevation view of left side of FIG. 1.

FIG. 6 is a plan view of the top of FIG. 1; and,

FIG. 7 is a plan view of the bottom of FIG. 1.
